LADDER ATTACHMENT

William Elwood Bowen, Atlanta, Ga.

Application April 15, 1952, Serial No. 282,437

2 Claims. (Cl. 248—210)

1

This invention relates to a ladder attachment and more particularly to a device for supporting paint buckets, brushes or other tools on a ladder rail.

In the drawing:

Figure 1 is a side view of the base or attaching plate.

Figure 2 is a side view of the base plate on an enlarged scale with the rail clamping members attached thereto;

Figure 3 is a view similar to Figure 2 but showing the device clamped to a ladder rail and between two of the rungs thereof;

Figure 4 is a detail view of one of the clamping members;

Figure 5 is a perspective view of the clamping member shown in Figure 4.

Figure 6 is a side view of the base plate with the adjusting plate pivoted thereon;

Figure 7 is a side view in elevation of the device.

Figure 8 is a top plan view of the device.

Referring to the drawings, 12 represents a flat circular plate which is provided with a continuous circular row of apertures 35 adjacent its periphery. A second substantially semi-circular flat plate 37 of substantially the same radius as the plate 12 is pivotally attached to one side of the plate 12 by a pivot member 36, as clearly shown in Figure 6. The plate 37 is adapted to be held in the desired position on the plate 12 by the engagement of the locking members 38 with certain of the apertures 35 in the plate 12.

The clamping means used to clamp the device on a ladder rail comprises two jaws 15 and 15' pivotally attached to the other side of the plate 12 by hinge members each of which comprises a pair of plates 17 and 20 pivotally connected together at 19. The hinge plates are slotted at 18 and 21 so that the hinges may be adjustably connected to the plate 12 and the jaws 15 and 15'. This adjustable feature allows the device to be mounted on ladder rails of different cross-sectional dimensions. The plates 17 are secured to the plate 12 by the bolts 14, while the plates 20 are connected to the jaws by the bolts 16. A plate 22 pivotally connected to one edge of the jaw 15' by the hinge 23 is adapted to lie flat against a side of a ladder rail and at one edge adjustably carries a latch member made up of the plate 26, the bolt 28, and the nut 29. The bolt 28 is pivotally connected to the plate 26 by a conventional hinge 27. The inner end portion 33 of the nut 29 is reduced to fit into an obliquely arranged recess 31 formed in a keeper plate 30 secured to the outer face of the jaw 15 so that when the nut 29 is tightened the two jaws

2

will be brought into clamping engagement with the ladder rail. The plate 26 is slotted at 25 to receive a bolt 24 for adjustably mounting the plate 26 on the plate 22.

5 A container 40 is detachably connected to the semi-circular plate by the screws 39 carried by this plate and passing through openings formed in the adjacent end wall of the container.

As shown in Figure 3, the attachment may be 10 secured to one of the faces of a ladder rail 11 by swinging the jaw members 15 and 15' into substantially parallel relation after which the plate 22 is swung over the rail with the portion 33 of the nut 29 engaging in the recess 31. The nut 15 29 is then tightened to securely clamp the jaws on the rail 11 between the rungs 10.

Having thus shown and described my invention, I claim:

1. A supporting attachment for use on a ladder comprising a circular flat plate adapted to be secured against the side of a ladder rail, said plate being provided with a circular series of apertures adjacent its periphery, a substantially semi-circular flat plate of substantially the same radius as the first-mentioned plate, said second-mentioned plate engaging and being pivoted to the first-mentioned plate, substantially diametrically disposed locking members mounted on said second-mentioned plate and adapted to be selectively engaged in certain of the apertures in said first-mentioned plate, a container having a side wall, means to detachably secure said container to said second-mentioned plate, said means comprising screws on said second-mentioned plate extending through openings in the side wall of said container, a pair of substantially parallel elongated clamping plates hinged to the first-mentioned plate and adapted to receive a ladder rail between them, means to adjustably secure one edge of said clamping plates on said 20 first-mentioned plate, a plate member pivoted to the opposite edge of one of said clamping plates, a laterally extending projection on the other clamping plate, an outwardly-opening recess in said projection, and a latch bolt on said plate member for engagement in said recess.

2. A supporting attachment for use on a ladder comprising a flat plate adapted to be secured against the side of a ladder rail, said plate being provided with a circular series of apertures, a second flat plate engaging and being pivoted to said first-mentioned plate, spaced locking members mounted on said second-mentioned plate and adapted to be selectively engaged in diametrically opposed apertures in said first-mentioned plate, a container having a side wall, screw

means to detachably secure said container to said second-mentioned plate, a pair of rectangular substantially parallel clamping plates, hinges connecting one edge of each of said clamping plates to the first-mentioned plate, a latch plate pivotally connected to the opposite edge of one clamping plate and carrying a latch bolt, and a keeper plate secured adjacent to the free edge of said other clamping plate and having a recess to receive said latch bolt.
